UNITED STATES PATENT OFFICE

THOMAS W. STONE, OF FORT WAYNE, INDIANA, ASSIGNOR TO THE WESTERN GAS CONSTRUCTION COMPANY, A CORPORATION OF INDIANA

TAR BATTER

Application filed January 25, 1930. Serial No. 423,392.

This invention relates to tar batter valves for gas generating sets and more particularly relates to means for cooling such valves without sealing the valves with cooling liquor 5 when they are open.

The invention also comprises the arrangement of the improved valves in gas apparatus in such manner as to prevent the entry of air or oxygen into the gas main connected 10 thereto.

When oil is used for carburetting the gas, enough tarry matter is formed to coat the seats of the tar batter valves as constructed heretofore and to stop leaks due to minor 15 irregularities. If water gas is made without enrichment, the absence of tarry matter allows any dust in the gas to wear the seats of valves not made in accordance with my invention and there is nothing present to prevent 20 leakage past worn places.

An object of my invention is to render the operation of the valve independent of an adhering coat of tar by having both the seat of the valve and the movable valve member 25 flooded with tar batter liquor while the valve is open.

The liquid flooding the seat and movable member forms a curtain or film extending from the seat to the member and gas passing 30 through the open valve must pass through this sheet or film of liquid.

The closing of the valve stops the flow of liquid if the valve closes perfectly but if any imperfection occurs in the seating, the liquid 35 continues to flood any parts of the seat and movable member not in firm contact, thereby substituting a harmless flow of liquid for a leakage of gas at the imperfection.

The constant presence of liquid in and 40 about the valve parts makes it unnecessary to have a dip pipe or to submerge the end of the pipe which serves as the seat of the valve in the liquor of the tar batter and a further object of the invention is to so rearrange the tar batter as to prevent any air leaking into the tar batter from entering the gas main of the gas generating set.

In the drawing:

Figure 1 is a vertical-sectional view 45 through the valve; and

Fig. 2 is a view partly in elevation and partly in vertical section showing the application of the valve to the tar batter of a gas-making set.

The valve shown in Fig. 1 comprises a disc 5 mounted on a stem 2, the valve disc when closed bearing against the seat 3 forming a part of a body 4.

The valve seat 3 is provided with a groove 5 which is cut in the valve body 4 at the time 60 of manufacture. A plurality of holes 6 conduct water, or tar batter fluid, from a casing 7 of channel iron into the groove 5. The casing 7 entirely surrounds the valve body 4, is supplied with water through a pipe 8 and is 65 welded to the valve body 4 by means of fillets 9.

The gas-making set shown in Fig. 2 comprises a generator 11, a carburetter 12, a superheater 13 and a tar batter 14. 70

A gas offtake pipe 15 connects the top of the generator to the top of the carburetter, a short pipe 16 connects the bottom of the carburetter to the bottom of the superheater and the pipe 17 connects the top of the superheater to the tar batter. A back run pipe 18 connects the bottom of the generator 11 to the tar batter 14 and gas leaves the tar batter through a gas main 19. 75

Air is supplied to the bottom of the generator through blast pipe 21 which is joined to the lower end of the back run pipe 18. Secondary air is supplied to the top of the carburetter through gas offtake 15 by means of secondary air blast pipe 22. The main air blast pipe is provided with a valve 23 and the secondary air pipe with a valve 24. A stack valve 25 is located at the top of the superheater. All of these valves are operated by means of hydraulic cylinders. 80

Steam is supplied to the base of the generator through a valve 26 and passes upwardly through the fuel bed 27 during the up-run period of the cycle. Down-run steam is supplied to the top of the superheater through 95 a valve 28. Both steam valves are operated with hydraulic cylinders that are in turn actuated by means of fluid from an automatic hydraulic control (not shown).

The carburetter is equipped with an oil 100

spray 30 and the generator is equipped with a fuel charging door 31. The tar batter is provided with an over-flow tank or sump 32. Pipes 17 and 18 are independent and are closed by blank plates 33.

A valve 35 controls the flow of gas from the pipe 17 into the upper part of the tar batter 14, the several parts of which valve correspond exactly to those of the valve shown in Fig. 1. The valve 35 is operated by means of a hydraulic cylinder 36, the valve stem connected thereto passing through stuffing gland 37. Any overflow of water from the pipe 8 drains into pipe 38 and into 10 the overflow tank 32 and prevents flooding of the pipe 17. Ordinarily there will not be enough leakage from groove 5 past seat 3 to cause any overflow through pipe 38.

Valve 40 controls the flow of gas from 20 pipe 18 into the top of the tar batter. The valve 40 is operated by cylinder 41. The stem 2 of the valve passes through a stuffing gland 42. Any excess of water entering the valve 40 through pipe 8 when it is closed 25 overflows through pipe 43, thereby preventing flooding of the back-run pipe 18. Such an excess of water would leak past the valve seat 3 only under unusual circumstances.

The tar batter is provided with a horizontal 30 diaphragm or partition 44 located about midway between the top and bottom thus dividing the tar batter into two superimposed compartments 14a and 14b. An overflow pipe 45 permits the tar batter liquor to flow 35 from the upper compartment 14a of the tar batter and maintain the level of the liquid at 46. The water flows into the lower compartment 14b of the tar batter through overflow pipe 45 which also permits gas to pass 40 downwardly and bubble through liquor contained in the lower compartment 14b of the tar batter 14. An overflow pipe 47 located above the level of the lower end of the pipe 45 maintains a normal level of liquor in the 45 lower part of the batter box effective to seal the pipe 45 against flow of gas in a reverse direction and drains into the overflow tank 32 which in turn is provided with an overflow pipe 48.

In operation, water or other liquid such as 50 tar batter liquor enters the annular chamber 7 formed of channel iron through the pipe 8 and enters the groove 5 through holes 6. As long as the valve disc 1 is held to its seat 55 3 and as long as the valve is in perfect condition, no liquid will flow in either direction from the groove 5. However, in the case of any slight irregularities or imperfections due to wear or the presence of dirt, liquid 60 will flow from the annular groove 5 at such places as the disc and seat fail to meet, thereby preventing any harmful leakage of gases through such places.

When the valve is open and the disc 1 is 65 submerged beneath the liquid level 46, an

annular skirt or cylindrical shaped sheet of liquid is projected from the seat toward the edges of the disc and against the surface of the liquid at 46. Any gas passing through the valve breaks or bubbles through this sheet 70 of water or tar batter liquor.

When valve 40 shown in Fig. 2 is open, back-run steam is passed into the top of the superheater 13 through valve 28 and stack valve 25 is closed at this time. The steam 75 passes downward through superheater 13 upward through a carburetter 12 and downward through the fuel bed 27 in the generator 11.

The resulting gas passes upward through 80 back-run pipe 18 into the upper part of the tar batter passing through the annular sheet of water showering down from the valve seat 3 of valve 40 towards the liquid level 46. The gas then passes downward through short 85 dip pipe 45 and from the lower part of the tar batter 14 it passes out through gas main 19.

When valve 40 is closed, valve 35 is open, up-run steam is passed through the valve 26 90 which generates gas by passing upward through the fuel bed 27. The resulting gas then passes down through carburetter 12 up through superheater 13 and through pipe 17 into the top of the tar batter, the stack valve 95 being closed at this time. The gas entering the tar batter through valve 35 passes through pipe 45 and into the gas main 19.

During the blow period of the cycle, the stack valve 25 is open, the valve 40 is closed 100 and the valve 35 is open. The main blast valve 23 is open admitting air to the bottom of the generator from blast pipe 21. Auxiliary blast valve 24 is open so that air from pipe 22 burns any carbon monoxide formed 105 by the passing of air upward through the fuel bed 27. The gases of combustion pass downward through the carburetter, upward through superheater and out through the stack valve. 110

If at this time any leakage through the closed valve 40 should occur, the small amount of air, instead of passing through pipe 45 and into the gas main 19, takes the path of least resistance through the open valve 35 and pipe 17 to the open stack valve. 115

Although the single embodiment of my invention that is illustrated is shown applied to a water-gas set equipped with a carburetter it is of even greater advantage when applied 120 to an uncarburetted set.

An important advantage of the valve is that the end of the pipe that serves as the seat of the valve need not be submerged in a cooling liquid or in tar batter liquor. Since the seat can be located above or independent of the liquor in the tar batter, two of such valves can be so arranged in the tar batter of a gas-making set that any air leaking through the back-run pipe at the time the fuel bed of 125 130

the generator is being blasted passes out of the stack valve.

Even such leakage, though harmless with this valve, is not apt to occur because when the valve is closed, any minute irregularity in the valve seat or valve disc will merely permit water to flow out of the annular groove in whichever direction the lack of firm contact occurs. The water pressure in the annular groove is always kept slightly higher than the pressure of the gas being controlled.

Wear of the valve seat 3 or valve disc 1 does not take place to any great extent because when the valve is open, there is so much water flowing out of the annular groove 5 and toward the submerged rim of the valve disc 1 that any dry dust particles in the gas cannot score or abrade the seat. Moreover, at the moment of closing the valve, the flow of liquid is such that any adhering abrasive particles are washed away.

Although the seat of the valve in use is not submerged in a solid body of liquid, the gas passing through the open valve is washed to the same degree as if the entire valve were submerged because it has to flow through the annular sheet of water or tar batter liquor that is projected from the valve seat against the surface of the liquid in which the valve disc is submerged in its open position.

I claim as my invention:

1. A tar batter for a gas generator, comprising two superimposed compartments, a pair of inlets in the upper compartment, valve members adapted to alternately and oppositely open and close said inlets, an overflow conduit for the lower compartment, a gas conduit leading from a point within said upper compartment to a point in the lower compartment lying below the level of said overflow conduit, and a gas offtake for said lower compartment.

2. A tar batter for a gas generator, comprising two superimposed compartments, a pair of inlets in the upper compartment, fluid-sealed valve members adapted to alternately and oppositely open and close said inlets, an overflow conduit for the lower compartment, a gas conduit leading from a point within said upper compartment to a point in the lower compartment lying below the level of said overflow conduit, and a gas offtake for said lower compartment.

55 In testimony whereof, I have hereunto subscribed my name this 23rd day of January, 1930.

THOMAS W. STONE.
